CARBURETOR

Harold H. Timian, Lake Orion, Mich., assignor
to Bendix Aviation Corporation, South Bend,
Ind., a corporation of Delaware

Application March 1, 1934, Serial No. 713,477

1 Claim. (Cl. 158—36.4)

This invention relates to carburetors and more particularly to a carbureting unit which will lift fuel from a storage tank positioned at a lower level than the fuel discharge nozzle of the carburetor.

A further object is to provide a carbureting unit in which the partial vacuum existing in the induction passage posterior to the throttle valve or in the intake manifold will be employed to operate a suction actuated fuel pump which may be formed as an integral part of the carburetor or as a separate unit connected therewith by suitable connections.

A still further object of the invention is to provide an improved carbureting unit of simplified construction which may be economically manufactured and which will be economical and positive in operation.

Another object is to provide a carbureting device in which the fuel level in the float chamber will be regulated by means of a float actuated suction responsive check valve communicating with the fuel pump so that the fuel level will be held continually between two limits determined by the setting of the check valve.

Other objects and advantages of the invention will be apparent from the following detailed description, and from the illustrative embodiments of the invention in the accompanying drawings, which are submitted merely for purposes of illustration and are not intended to define the scope of the invention, reference being had for that purpose to the subjoined claim.

In the drawings, wherein similar reference characters refer to similar parts throughout the several views:

Figure 1 is an elevation showing one form of carbureting device embodying the invention, fitted to an internal combustion engine;

Figure 2 is a vertical section of the same;

Figure 3 is a diagrammatic view showing a portion of the diaphragm actuating mechanism; and

Figure 4 is a vertical section showing another form of the invention.

Referring more particularly to Figure 1, there is shown an engine 10 having an intake manifold 12 equipped with a carbureting unit 14 of the present invention for lifting fuel from a supply tank 16 positioned at a lower level than the carbureting device.

Referring now to Figure 2, we find a float chamber 18 equipped with a float 20 having an arm 22 fixed thereto and pivoted on pin 24. The upper surface of float 20 engages a slidable spring

pressed valve member 26 when the fuel level in float chamber 18 rises to a given level. Valve member 26 will then be urged upward by float 20 compressing spring 28 and raising disk 30 from its seat 32 and allowing suction from inlet manifold 12 transmitted through duct 34 to be vented to the atmosphere by means of passage 36, cross bore 38, through chamber 40 and out vent ports 42. Chamber 40 is filled with loose packing material 44 to form an air cleaner.

When valve member 26 is closed the suction transmitted through duct 34 is transmitted by means of duct 44 to a fluid tight chamber 46 in which a flexible diaphragm 48 made of leather or other flexible material forms one wall. The diaphragm is fixed at its outer rim between two surfaces 50 and 52 fixed together by any convenient fastening means 54, and is actuated in one direction by suction from duct 44 and in the opposite direction by means of a coiled spring 56.

Diaphragm 48 is engaged between a spring seat 58 and a flat disk 60 mounted on a threaded stud 62 fitted with a lock nut 64. Threaded stud 62 is provided with a shank 66 and a cross member 68, better illustrated in Figure 3. Shank 66 fits into a groove 72 formed between a pair of ears 70 carried by a guide 74. Guide 74 is slidably mounted in a cylinder 80 provided with a passage 82 communicating with chamber 84 which communicates with atmosphere by means of vent 86. Chamber 84 is filled with loose packing material 88 to form an air cleaner.

A liquid pumping chamber 90 is provided on one side of diaphragm 48 and communicates with supply tank 16 by means of duct 92 fitted with gravity seating disk check valve 94 having a stop member 96 to prevent disk 94 from moving so far out of place that it could not return. The upper portion of chamber 90 is fitted with a similar disk check valve 98 provided with a stop member 100 and communicates with the bottom of float chamber 18 by means of duct 102.

The operation of this device is as follows. Assume that the engine is running and that float 20 is in the position shown in Figure 2. Slidable valve member 26 is held in its uppermost position by float 20, compressing spring 28 so that suction transmitted from intake manifold 12 through duct 34 is vented to atmosphere through passage 36, cross bore 38, chamber 40 and vent ports 42. In this position no fuel will be pumped and the engine 10 will operate on the fuel present in float chamber 18 until the liquid level therein drops to such a point that float 20 will allow valve member 26 to move downward until

disk 30 is urged against its seat 32 by spring 28. Passage 36 is then closed to suction transmitted through duct 34 and it will be transmitted by means of duct 44 to fluid tight chamber 46 where 5 a partial vacuum will be created which will draw diaphragm 48 to the right compressing spring 56 and drawing fuel from storage tank 16 through duct 92 into chamber 90. As diaphragm 48 moves to the right, guide 74 moves in cylinder 80 until cross bore 78 is lined up with passage 82 whereupon chamber 46 is vented to atmosphere by means of longitudinal bore 76, cross bore 78, chamber 84 and vent 86. When chamber 46 is thus vented coiled spring 56 urges diaphragm 48 to the left closing check valve 94, opening check valve 98 and pumping fuel from chamber 90 through duct 102 to float chamber 18.

As soon as guide 74 moves to the left cross bore 78 and passage 82 are thrown out of alignment and suction from duct 44 will again be exerted in chamber 46 to actuate diaphragm 48. This process continues until the fuel level in float chamber 18 rises to such a point that float 25 20 lifts valve member 26, thereby venting the system through the passages associated with the top of float chamber 18, and renders the fuel pumping apparatus inoperative.

Figure 4 illustrates a device similar in many respects to that disclosed in Figure 2, but having the fuel pump formed as an integral part of the carburetor instead of being formed as a separate unit connected by ducts as disclosed in Figure 2.

Figure 4 illustrates a carbureting device of the down-draft type having a main induction passage 120 with a choke valve 122 to regulate the amount of air admitted through air horn 124. Fuel is admitted to induction passage 120 from 30 float chamber 125 by means of a fuel discharge nozzle 126 terminating in the most restricted portion of a primary venturi 128 which in turn discharges into the most restricted portion of a secondary venturi 130. The rate of flow of the 35 combustible mixture formed in the induction passage is regulated by means of a throttle valve 132 mounted in the walls of the main induction passage 120.

Suction is transmitted from induction pas-

sage 120 posterior to throttle valve 132 by means of duct 134 which leads to a suction actuated fuel pump 138 similar to that disclosed in connection with Figure 2. An auxiliary duct 136 communicates with duct 134 and leads to a 5 downwardly extending passage 140 leading to float chamber 125. Passage 140 receives a slideable valve member 142 having a disk-like member 144 fixed thereto. Disk member 144 cooperates with a seat 146 to close auxiliary duct 136 10 when valve member 142 is urged downwardly by spring 150. Valve member 142 is actuated by float 148 which is sensitive to variation in fuel level in chamber 125.

When the fuel level in chamber 125 is high 15 the top of float 148 engages the end of valve member 142 and forces it up compressing spring 150 and raising disk 144 from its seat 146 so that suction from duct 134 may be by-passed through float chamber 125 thereby interrupting the action of fuel pump 138 until the fuel level in float chamber 125 has lowered to such an extent that disk 144 may be urged against its seat 146 by spring 150 whereupon suction will again be transmitted to pump 138 through duct 134.

Fuel pump 138 is identical in construction and operation with that disclosed in connection with Figures 2 and 3. Corresponding parts have been numbered the same as in those figures. Fuel is transmitted from chamber 90 to float chamber 125 by means of duct 152 communicating therewith.

I claim:

In combination a carburetor for an engine having a source of suction, a fuel reservoir, a float controlling the fuel level in the reservoir, a differential pressure actuated fuel pump comprising a diaphragm, a fluid pumping chamber, and an actuating chamber, connecting means between the actuating chamber and the source of suction, yielding means urging the diaphragm toward one extreme position, venting means operable to vent the actuating chamber when the diaphragm approaches one extreme position, and means operable by said float to vent the connecting means and render the fuel pump inoperative when said float approaches one extreme position.

HAROLD H. TIMIAN.
